JOSEPH H. DWORK, OF NEWARK, NEW JERSEY

MOP WRINGER

Application filed October 11, 1930. Serial No. 488,072.

My invention relates to mop wringers and it consists in the constructions, arrangements and combinations of parts herein described and claimed.

5 An object of the invention is the provision of a mop wringer incorporated as an integral part of a water pail and wherein a part of the wringer proper constitutes the bail of the vessel.

10 A further object of the invention is to provide a base for the pail so shaped as to accommodate a bearing for the foot treadle.

A still further object of the invention is to provide a mop wringer in which the foot 15 treadle acts as a support for the receptacle, to prevent tipping thereof during the wringing operations.

Additional objects, advantages and features of the invention will be apparent from 20 the following description and drawings forming a part of this application wherein:

Figure 1 is a perspective view of my invention, in position to receive a mop.

Figure 2 is a vertical section showing the 25 parts in wringing position.

Figure 3 is a top plan view.

Figure 4 is a fragmentary perspective view of a modified form of bracket.

In carrying out my invention, I provide 30 a receptacle 10, which may be of any well known construction, but having the bottom 11 disposed a distance from the supporting edge 12, thereby providing a recess 13. The bottom 11 is centrally and transversely 35 dished as at 14 and within this dished portion, there is provided a bearing 15.

A foot treadle generally indicated by the 40 reference character 16 is oscillatably mounted within the bearing 15 and comprises a heavy wire 17 of a length to extend beyond the outer circumference of the receptacle, the ends being bent at right angles as at 18 and thence inwardly as at 19 so as to lie in the same plane as the portion 17, but stops 45 short of the sides of the receptacle.

Upon one side of the receptacle I provide 50 a bracket 20 of a shape to fit the inner circumference of the receptacle, this bracket being secured to the receptacle by rivets, or otherwise. The bracket 20 is suitably aper-

tured at diametrically opposite points for mounting of a revoluble roller 21. The bracket 20 also includes guides 22, disposed adjacent the ends of the roller 21, which serve to retain the mop clear of the trunnions of the roller. 55

From this construction it will be apparent that the bracket serves to reinforce the receptacle as well as afford support for the roller. 60

Ears 23 are mounted upon the upper edge of the receptacle 10, the axis of these ears being in a plane parallel to the longitudinal axis of the roller 21. 65

A handle 24 is pivoted in respective ears 23. The handle in the present instance, is formed from strap iron bent intermediate its ends to provide a bight portion 25, the leg portions 26 thereof extending rearwardly (as seen in Fig. 2), and are slightly canted 70 forwardly, as at 27. Intermediately of the legs 26, I provide an ear 26', extended at right angles, and between these ears there is a revoluble roller 28. The handle is of such length as to dispose the roller 28 above 75 the roller 21. It should be noted that the ears 26' dispose the rollers well in advance of the bight portion 25, thus affording ample clearance for a mop.

The leg members 26 are canted forwardly 80 in order to prevent the roller 28 in mutual contact with the roller 21, which is disposed well within the receptacle 10.

Upon opposite sides of the handle 24 there is pivoted a link 29 which extends downwardly and is pivotally mounted upon the portion 19 of the foot treadle 16. 85

When it is desired to employ the handle 24 for transporting the pail, the handle is grasped centrally of the bight portion and raised upwardly, when the pail may be readily carried. 90

It should be noted that the foot treadle 16 herein described provides a bracing means for the receptacle extending laterally through the center of the receptacle, and it will be therefore seen that upsetting or tipping of the pail, during wringing operation is eliminated. 95

In the operation of my device the handle 100

24 is in its raised position as illustrated in Fig. 1. The mop is positioned upon the roller 21 with the mop strands confined upon the roller by the guides 22, the loose ends of the 5 mop extending into the receptacle 10. The operator now places one foot upon one of the treadles 16 and exerts a downward movement on the treadle. Such downward movement of the treadle pulls upon the arm 29 which 10 in turn swings the handle 24 toward the roller 21. The operator now places his other foot upon the treadle at the opposite side of the receptacle and exerts a final pressure upon the treadles to bring the rollers 21, 28 into 15 tight engagement with the interposed mop. Such pressure is retained upon the rollers, and the handle of the mop is drawn outwardly causing the strands of the mop to be compressed between the rollers thereby expelling the water therefrom.

20 From the foregoing it will be seen that I have provided a mop wringer of simple construction, and one which embodies a construction preventing tipping of the receptacle during wringing operations.

25 In Fig. 4, I have illustrated a modified form of bracket, in which an ear 30 is formed integrally with the bracket 20. In the use of this form of bracket, the ears 23 of the receptacle are omitted, the ears 30 being bent so as to overlie the rim of the receptacle.

What is claimed is:

1. In a mop wringer, a receptacle having a bottom transversely dished, a bearing 35 mounted therein, a treadle member oscillatably mounted in said bearing, and said treadle member extending laterally upon opposite sides of said receptacle to provide a support for said receptacle.
2. In a mop wringer, a receptacle having a bottom, a bearing mounted transversely thereof, a wringer mounted upon the upper end of said receptacle, an elongated member 45 extending through said bearing and extending upon opposite sides of said receptacle and forming a support therefor, said elongated member having its ends bent to form foot treadles, and a link connected between said treadle and wringer.
3. In a mop wringer, the combination with a receptacle, and a roller mounted therein, of a movable frame having a revolvable roller, a bearing on the bottom of said receptacle, an elongated member oscillatable therein, and 55 projecting upon opposite sides of said receptacle forming a lateral support for said receptacle, the ends of said elongated member being bent to form foot treadles, and a link connected between said movable frame and said foot treadles, whereby said rollers may be brought into co-operative positions.
4. In combination with a receptacle, a mop wringer comprising a bracket secured upon the inner circumference thereof, a roller carried thereby and disposed transversely of

said receptacle, ears upon the upper edge of said receptacle, and in opposed relation, a bail pivoted in said ears, said bail being bent to form a bight portion, a roller revolvably mounted in said bight portion, said bight portion being canted forwardly to dispose said roller at an angle to said first named roller when brought into cooperative position, a treadle member mounted transversely of said receptacle and projecting upon opposite sides thereof, and link members connecting said bail and foot treadle.

JOSEPH H. DWORK.
